Primary Examiner — Holly E Thurman*Assistant Examiner* — Altaira J Swangin(74) *Attorney, Agent, or Firm* — Jose Cherson Weissbrot(57) **CLAIM**

The ornamental design for an egg decorating kit, as shown and described.

DESCRIPTION

FIG. 1 is a top, front perspective view of an egg decorating kit, showing my new design;

FIG. 2 is a bottom, rear perspective view thereof;

FIG. 3 is a rear perspective view thereof;

FIG. 4 is a right side elevation view thereof, the left side elevation being a mirror image of FIG. 4;

FIG. 5 is a front elevation view thereof;

FIG. 6 is a rear elevation view thereof;

FIG. 7 is a top plan view thereof; and,

FIG. 8 is a bottom plan view thereof.

The broken lines used in the figures depict portions of the egg decorating kit that form no part of the claimed design.
